ATTORNEYS

UNITED STATES PATENT OFFICE.

CLIFFORD M. HADDOX, OF CHARLESTON, WEST VIRGINIA.

SHOE TONGUE.

Application filed February 27, 1924. Serial No. 695,504.

To all whom it may concern:

Be it known that I, CLIFFORD M. HADDOX, a citizen of the United States, and resident of Charleston, in the county of Kanawha 5 and State of West Virginia, have invented certain new and useful Improvements in Shoe Tongues, of which the following is a specification.

My invention relates generally to improvements in shoe tongues, more particularly to shoe tongues having means whereby they may be retained in place between the edge portions of the upper of a shoe, and it consists in the constructions, combinations and 15 arrangements herein described and claimed.

An object of the invention is to provide a simple and inexpensive attachment adapted to be readily applied to the upper end portion of a shoe tongue and adapted when in 20 applied position on a shoe tongue to engage with a shoe lace in such manner as to hold the shoe tongue against slipping down in the shoe or to one side and to prevent the tongue from being wrinkled or crumpled.

25 A further object of the invention is to provide a tongue supporting attachment of the character described which will be hidden from view by the side portion of the shoe upper when the attachment is in applied 30 position on the shoe tongue and which will not cause discomfort to the wearer of the shoe.

Other objects and advantages will be apparent from the following description, considered in conjunction with the accompanying drawings, in which—

Figure 1 is a perspective view showing a shoe having the tongue thereof equipped with an attachment embodying the invention. 40

Figure 2 is a fragmentary plan view showing the tongue and the attachment thereon,

Figure 3 is a relatively enlarged vertical 45 section along the line 3—3 of Figure 2.

As is well known, the tongue of a lace shoe is secured at its lower end to the shoe vamp and extends upwardly on the instep of the foot of the wearer in position to be 50 overlapped by the adjacent edge portions of the shoe upper. The shoe tongue is made of pliable leather. In a shoe in which the edge portions of the shoe upper are connected by a lace in the usual manner, the 55 tongue is likely to slip downward or laterally and to be twisted, wrinkled or

crumpled, particularly if the lacing should be loosened, if the tongue should not have been sewed to the vamp so that it will normally extend straight between the edge 60 portions of the upper or if the wearer of the shoe should have a weak ankle, causing twisting or other movement of the foot in the shoe. When the tongue has been displaced, the shoe is not closed between the 65 edge portions of the upper. Moreover, the displacing of the tongue permits the lacing of the shoe to press against the foot of the wearer and to cause discomfort.

An attachment embodying the invention 70 may be secured to the tongue of the shoe and then engaged with the lace of a shoe to hold the tongue securely in position. Figure 1 illustrates a shoe, designated 1, provided with the usual tongue 2 which is secured only at its lower end and is adapted when in extended position on the instep of the foot of a wearer to be overlapped by the edge portions 3 of the shoe upper. The edge portions 3 of the shoe upper are provided with eyelets 4 through which a lace 5 is threaded, the end portions of the lace being adapted to be tied together when the lace has been drawn taut to hold the edge 75 portions 3 in overlapping relation to the 80 tongue 2.

The shoe described so far is ordinary in construction and may vary considerably in details from the shoe which is illustrated in Figure 1. The shoe may be a "high shoe" 90 and in fact the invention is particularly well adapted for use in holding the tongue of a "high shoe" in place, as will be understood from the following:

An attachment embodying the invention 95 comprises a slightly elongated strip or tab 6 made of pliable leather or like material and provided adjacent to one end thereof with an eyelet 7. The tab 6 is secured adjacent to its other end to the shoe tongue adjacent to the upper end of the latter and preferably also adjacent to a lateral edge of the tongue, as by means of stitching 8. The tab 6 therefore overlies an upper corner portion of the tongue. Tabs 6 may be secured upon both the upper corner portions 100 of the tongue, if desired.

From the foregoing description of the various parts of the device, the operation thereof may be readily understood. When 105 the shoe is fastened, the tongue is arranged in extended position on the instep of the

foot of the wearer so that the tongue will be smooth and will be in position to be overlapped by the edge portions of the shoe upper when such edge portions have been secured by means of the lace 5. One end portion of the lace 5 is threaded through the eyelet 7 of the tab before being inserted through one of the eyelets (preferably the upper) 4 of the adjacent edge portion of the shoe upper. Obviously, when the end portions of the lace have been tied together so that the lace is taut, one of the edge portions 3 of the shoe upper will overlie the tab 6 and conceal the latter from view. At the same time, the tongue 2 will be retained in extended position and will be prevented from slipping downward on the instep or laterally underneath one of the edge portions of the shoe upper and also from becoming wrinkled or twisted.

Obviously, my invention is susceptible of embodiment in forms other than that illustrated in the accompanying drawings and I therefore consider as my own all modifi-

cations and adaptations of the form of the device herein described as fairly fall within the scope of the appended claims.

I claim:

1. The combination with the tongue of a lace shoe of a strip of pliable material secured at one end to a lateral edge portion of said tongue adjacent to the upper end of the tongue, said strip having an eyelet adjacent to its other end, said eyelet being adapted to permit of the threading of the lace of the shoe therethrough.

2. The combination with the tongue of a lace shoe of a relatively short and narrow strip of pliable material secured at one end to the tongue adjacent to a lateral edge and the upper end of the tongue, said strip having an eyelet adjacent to its other end through which the lace of the shoe may be threaded, said strip also being adapted to be completely overlapped by an edge portion of the shoe upper when the lace has been tied.

CLIFFORD M. HADDOX.
